Int. Cl. D24—02

FIG. 1

FIG.2

FIG.3

FIG.4

FIG. 1 is a perspective view of a linear accelerator for cancer radiotherapy or the like showing our new design;

FIG. 2 is a front elevational view, to an enlarged scale;

FIG. 3 is a side elevational view, to an enlarged scale, the opposite side being substantially a mirror image;

FIG. 4 is a top plan view, to an enlarged scale; and the rear is substantially plain.

The dominant features of the design reside in the portions shown in full lines.

I claim:

The ornamental design for a linear accelerator for cancer radiotherapy or the like, as shown and described.
